S. STEINMAN

LATCH DEVICE FOR HAND BAGS

Filed Nov. 3, 1925

UNITED STATES PATENT OFFICE.

SAMUEL STEINMAN, OF BROOKLYN, NEW YORK.

LATCH DEVICE FOR HAND BAGS.

Application filed November 3, 1925. Serial No. 66,486.

My invention relates to a new and improved latch device for hand-bags.

One of the objects of my invention is to provide a latch device which shall have a springy or resilient action but which will not require the use of any springs in the latch member or directly associated with the latch member.

Another object of my invention is to provide a latch device of great simplicity, cheapness and durability.

Another object of my invention is to provide a latch device, the use of which will not injure or twist the frame members in any manner.

Other objects of my invention will be set forth in the following description and drawings which illustrate a preferred embodiment thereof, it being understood that the above general statement of the objects of my invention is intended to generally illustrate the same and not to limit it in any manner.

Fig. 1 is a perspective view of a hand-bag embodying my invention.

Fig. 2 is a detail front elevation showing the latch device in the closed or operative position.

Fig. 3 is a view similar to Fig. 2 but showing the latch device in the open or inoperative position.

Fig. 4 is a section on the line 4—4 of Fig. 2 and is partially in elevation.

Fig. 5 is a section on the line 5—5 of Fig. 3.

The device has frame members 1 and 2 connected by a pintle or pivot member 10. The frame members 1 and 2 have the fabric 3 connected thereto in any ordinary manner so as to provide a complete bag. The ends

40 of the frame members 1 and 2 which are directly adjacent the pintle or pivot member 10, are adapted to contact with each other while the frame members 1 and 2 are still slightly separated from each other. Hence,

45 in order to move the frame members 1 and 2 into the completely closed position, it is necessary to exert a slight force and the resiliency of the frame members 1 and 2 is sufficient to enable them to be moved to the completely closed position. This slight yield of the frame members with respect to

their hinge portions can be secured in any other or suitable manner.

The frame member 1 has two posts 6 connected at the top thereof and the frame member 2, which may be designated as the rear frame member, has two similar posts 9 connected at the top thereof. Each post 9 is aligned with one of the posts 6. A latch member 4 having a projecting finger-hold 5 is pivoted at 8 to the latch posts 9. As clearly shown in Fig. 3, the latch member 4 also has a tongue 7 and this tongue 7 is adapted to enter the space between the posts 6, when the frame members 1 and 2 have been forced to the completely closed position. When the latch member 4 is forced to the locking position shown in Fig. 4, for example, the lateral flanges of the finger-hold 5 engage the front posts 6 so that when the device is in the closed position, the flat inner faces of the said flanges are in full contact with the front faces of the posts 6.

It requires a slight amount of force to actuate the latch member 4 into the operative or into the inoperative position.

When the latch member is moved to the operative position, the tongue 7 enters the spaces between the front posts 6 and the rear posts 9 so that any lateral twisting of the frame members is prevented. This prevents any injury to the pintle or pivot member 10, no matter how many times the bag is opened or closed.

It is obvious that no springs are directly associated with the latch member 4, but that the natural resiliency of the bag frame is sufficient to keep the latch member 4 firmly in the operative position.

While I have shown my latch device as applied to the frames of hand-bags, I do not limit the scope of my invention to any particular type of bag, box or the like.

I have shown a preferred embodiment of my device, but it is clear that numerous changes and omissions could be made without departing from its spirit.

I claim:

In a bag of the type having a frame comprising front and rear frame members pivotally connected to each other, separated upwardly front posts provided on said front

frame member at the top thereof, having separated upstanding rear posts provided on said rear member, said rear posts being substantially aligned with said front posts, and 5 a latch member located intermediate said rear posts and pivotally connected thereto, said latch member having a tongue adapted to enter between the front posts and also

having a head adapted to engage the front faces of said front posts, said front faces of said front posts being planar and the engaging surfaces of said head being correspondingly shaped. 10

In testimony whereof I affix my signature.

SAMUEL STEINMAN.
